SECTIONAL CANOE

Felix A. Aimonetti, Binghamton, N. Y., assignor
to Link Aviation, Inc., Binghamton, N. Y., a
corporation of New York

Application August 7, 1944, Serial No. 548,468

2 Claims.

(Cl. 9—2)

1

This invention relates to a sectional boat, canoe or the like of the type wherein the main sections of the device may be readily taken apart and after being so taken apart may, when desired, be readily assembled in its usable state, suitable clamps being provided to hold the various parts of the structure in their proper relative positions. The prime purpose of providing such a device is to render it, when disassembled, more easily handled and transported to and from the point of use.

Inasmuch as such boats, canoes, and similar vessels are built in sections, suitable means for making the device waterproof must be provided. One such method is the provision of a cover or shoe, made of canvas or other suitable watertight, flexible material which may be fit over the entire hull of the assembled structure, thereby rendering it waterproof.

However, such structures provided with canvas covers have not become widespread in use because of the great length of time required to put the canvas cover on the sections after they have been assembled.

Another disadvantage of the prior art covers is that the type of lacing used makes it difficult to easily secure the entire canvas cover snugly to the assembled sections. Also, the location of the holding means which hold the lacing has been such that much inconvenience is experienced in engaging the lacing therewith.

It is the general object of my invention to overcome the above stated deficiencies of the prior art.

In the preferred embodiment of my invention this is accomplished by attaching to the upper edge or edges of the cover a strong, resilient cord. At suitable points, spaced a few inches apart, the cord is attached to the canvas cover, as by suitable stitching. Then, there are provided on the outside of the hull near the gunwales at a point above the top of the canvas cover a plurality of holding members, so that the cord may be pulled up and held thereupon by virtue of their elasticity.

By my invention the canvas cover may, therefore, be easily, quickly and securely attached upon the outside of the assembled boat or canoe.

Another object of my invention is to provide a detachable cable, easily affixed to the canoe along the outside of the cover, whereby the cable may form a keel upon which the canoe may slide when outside the water, thereby preventing undue damage to the canvas cover. The cable may or may not be affixed to the canvas cover.

In order that the preferred embodiment of my invention may be more fully understood reference is made to the accompanying drawings, in which

5 Fig. 1 is a plan view of the device shown in assembled condition.

Fig. 2 is a view of the stern of a canoe, certain parts being cut away for purposes of illustration.

10 Fig. 3 is a view partly in cross section taken along the line III—III of Fig. 1, showing in detail one type of the preferred clamping means.

Fig. 4 is a detailed view of another of the forms of clamping means which may be used with my invention.

15 Fig. 5 is a detailed view of another means used in my invention for holding the main sections of the hull as well as the thwart in proper position.

Fig. 6 is a perspective view of a part of one of 20 the hull sections showing the dowel pins and holes.

Fig. 7 is a perspective view of a part of a 25 canoe, showing the canvas cover, cord, method of attaching the lacing to the canvas cover, and the holding members on the hull sections with which the cord may be engaged.

Fig. 8 is an elevation of a part of the canvas cover and cord.

Fig. 9 is a detailed view of the members 30 attached to the canoe sections for engaging the cord.

My invention will be illustrated when incorporated in a sectional canoe of the type shown in Fig. 1 but it should be borne in mind that it 35 may be used in other types of water-going craft. In that figure the longitudinal center line of the canoe is designated 10, the center line of course dividing the device equally. Transverse of the center line are the lines 12, 14 and 16 which extend from the port gunwale 15 to the starboard gunwale 17 of the canoe.

The longitudinal center line 10 and transverse lines 12, 14 and 16 divide the canoe into eight major sections designated generally 18, 20, 22, 40 24, 26, 28, 30 and 32, and the canoe is preferably built so that each of these eight sections may be detached from the neighboring sections or attached to the neighboring sections, as the case 45 may be. When detached the various sections may be "nested" in the usual manner.

The fore and aft decks are designated 34 and 36 and they may be detachably connected to the associated stem and stern hull sections in any conventional manner.

55 A forward seat 38 and a rearward seat 40 are

also provided as is a central thwart 42. The seats may be detachably connected to the hull sections in any suitable manner and the thwart is detachably connected to the hull sections in a manner which will be hereinafter disclosed.

Each of the hull sections has a plurality of rigid ribs 44 which extend transversely of the canoe and are suitably curved to properly shape the canoe. Suitable outside covering material 46 is attached to the ribs, and this covering material may be of any suitable type such as canvas, plywood or plastic material.

Still referring to Fig. 1, it will be seen that each of the main eight sections of the canoe has a longitudinal keel piece 48 or 49, the numbers 48 designating the keel pieces of the four starboard sections 18, 22, 26 and 30 and the numbers 49 designating the keel pieces of the four port sections 20, 24, 28 and 32. The keel piece of each section abuts the keel piece of the transversely adjacent section. Further, each of the main eight sections has a rib 43 at its extreme end or ends which abut another section of the device. It will be seen in Fig. 1 that a plurality of clamps 50 extending transversely on the inside bottom of the canoe are provided to hold the sections of the canoe tightly against the transversely opposite sections. Also, a plurality of the same types of clamps 50 are provided to hold the various sections tightly against the longitudinally adjacent sections.

There is shown in Fig. 2 at the stem a second type of clamp 54, three in number, which are used to hold the adjoining transverse sections of the canoe in proper relative positions. Similarly, three of these same type of clamps 54, although not shown, are correspondingly placed in the stern of the canoe for the same purpose.

Reference is now made to Fig. 3 which shows in detail the previously-mentioned clamps 50. Shown in Fig. 3 is the watertight covering material 46 and the ribs 44 to which the covering material is attached. Rigidly attached to the upper surface of the ribs 44 are a pair of filler blocks 56 and 58. Block 56 is rigidly affixed to starboard keel 48 in a suitable manner and the keel 48 is also rigidly affixed to the starboard rib 44. At the same time, the port keel 49 is rigidly affixed to filler block 58 and to the port rib 44. A stud plate 60 having a stud 62 rigidly attached thereto is affixed upon filler block 56 by means of screws 64 and clasp plate 66 is rigidly affixed to filler block 58 by means of screws 68. Bracket 70 is rigidly affixed to plate 66 in a suitable manner and pivot 72 is provided so that the clasp lever 74 may pivot therearound. Clasp 76 is pivotally connected to clasp lever 74 and may encircle stud 62 as shown, stud 62 being grooved for receiving clasp 76. When clasp lever 74 is raised clasp 76 may be disengaged from stud 62, and when clasp lever 74 is depressed with clasp 76 encircling stud 62, as shown in Fig. 3, it will be understood that keel section 48 will be drawn tightly against the keel section 49.

Also seen in Fig. 3 is a dowel pin 78 fixedly held by the keel section 49 which is drilled at 79 to receive the dowel pin. Keel section 48 has a corresponding hole 80 to receive pin 78. This conventional dowel arrangement is provided at a plurality of suitably spaced places along the keel members, and the thick abutting ribs 43 as seen in Fig. 6 have the same arrangement, the dowels and dowel holes in that figure also being designated 78 and 80, respectively.

Reference is now made to Fig. 4 which shows

the type of clamp previously mentioned and designated in Fig. 2 by 54. As seen, cam hinge bracket 86 is rigidly affixed to starboard keel section 48 by means of screws 88 and the stud 90 is integral with angle 92 which is suitably rigidly affixed to port keel section 49. Cam support bracket 94 is pivotally mounted upon pin 96 which is held by cam hinge bracket 86 and cam 98 is rotatably mounted by means of stud 100 held by flange 102 integral with bracket 94. Arm 104 is integral with cam 98. When arm 104 is turned 180° from the position shown in Fig. 4, cam 98 becomes disengaged from stud 90 and it will be realized that bracket 94 may be moved to the vertical position whereupon keel members 48 and 49 may be separated. Similarly, with arm 104 in that position, it will be realized that when keel member 48 is placed adjacent member 49, bracket 94 may be moved to the position shown in Fig. 4 and the movement of arm 104 through 180° to the position shown in Fig. 4 pulls keel members 48 and 49 together thus providing a tight fit. This type of clamp designated 54 is used in the stem and stern of the device because at those positions lack of space prohibits the use of the type of clamp designated 50 and disclosed in detail in Fig. 3.

Fig. 5 discloses the detailed means of affixing the thwart 42 to the main hull sections of the canoe and at the same time providing a clamp for holding the longitudinally adjoining sections 22 and 26, on the one hand, and 24 and 28 on the other, in proper relative position.

As seen in Fig. 5, the gunwale 15 of each section 24 and 28 is shown to comprise an outer member 106 or 106' and an inner member 108 or 108', the latter numbers designating the part of section 24. Ribs 43 and 44 are fixedly held therebetween by means of screws 45. Plate 110 is rigidly affixed to inner gunwale 108 of section 28 by means of screws 112 and stud 114 is fixedly attached to plate 110. A second plate 110' is rigidly affixed by means of screws 112' to the inner gunwale member 108' of section 24. Stud 114' is rigidly affixed to plate 110'.

Angle bracket 116 is provided and thwart 42 is rigidly affixed to angle bracket 116 by means of screws 118 while thwart clamp 120 is pivotally mounted with respect to angle bracket 116 by means of stud 122 which is rigidly affixed to angle bracket 116. A pair of clearance holes (not shown) are provided in angle bracket 116 to allow the passage therethrough of grooved studs 114 and 114' and a pair of curved slots 124 are provided in clamp 120.

With the just described construction it will be appreciated that when thwart 42 is detached from the sections 24 and 28 it may be properly positioned with respect to sections 24 and 28 by having clamp 120 clockwise 90° from the position shown in Fig. 5, this positioning of clamp 120 being possible by virtue of the clearance 126 between the end of thwart 42 and the vertical component of angle bracket 116. Then, by positioning studs 114 and 114' with respect to angle bracket 116 as shown in Fig. 5, the counterclockwise rotation of clamp 120 to the position shown in Fig. 5 not only draws the longitudinally adjoining sections 24 and 28 together so that they closely abut along the line 14, but at the same time, inasmuch as an arrangement like that shown in Fig. 5 is provided at the port end of thwart 42 and where sections 22 and 26 adjoin, thwart 42 is positioned by the just described arrangement to hold the starboard and port gun-

wales in their proper relative positions. Also, sections 22 and 26 are pulled together.

Reference is now made to Fig. 7 which shows the canvas cover 130 which is shaped in accordance with the outside of the hull sections when assembled. The canvas cover is also shown in Fig. 3. A strong, resilient cord 132 is shown in Figs. 7 and 8. This cord, as seen in Fig. 8, runs along the top edge of cover 130, when the canvas cover is removed from the assembled canoe, and at suitably spaced points the cord is preferably, although not necessarily, stitched by strong thread 134 which passes through the canvas cover and tightly encircles cord 132 so that the cord can not slip through the noose formed by the threads. The cord 132 may be in a single piece completely encircling the top of the canvas cover, or separate pieces may be used.

Also seen in Fig. 7 are a plurality of cord holding members 136 positioned a substantial distance above the top edge 131 of the cover. Fig. 9 is a detailed view of one of the members 136, and it will be seen that they comprise an ordinary screw 138 passing through a member 140 having a groove 142 for receiving the cord.

With the just described arrangement of cover, cord, and cord engaging members it is clear that after the canvas cover has been placed upon the outside of the assembled sections, the cord may be easily and quickly grasped, pulled up and engaged upon the cord holding members. It is not necessary to thread a long lace successively through a series of holes, taking great care to be sure that the lace is tight before it is tied. The provision of the cord engaging members a substantial distance above the points at which the cord is attached to the cover, in combination with a strong resilient cord assures that the cover will snugly fit the canoe. Further, the cord engaging members, being located upon the outside of the sections, further simplifies the cover securing process.

Referring now to Fig. 3 it will be seen that a reinforcing strip 144 may be sewed on the outside of the canvas cover 130 along the part of the cover below the keel sections 48 and 49, and that a cable 146 may be placed below the reinforcing strip. Cable 146 may be provided at one end with a conventional hook (not shown) which fits into the eye 148, affixed to hull section 20 as shown in Fig. 2. Referring to Fig. 7, the other end of cable 146 carries an eye 150 which may be engaged by hook 152 carried by lever 154 which is pivotally attached to bracket 156 fixedly mounted upon keel section 48. Bracket 156 and lever 154 are preferably of the off-center clamping type.

The cable 146 may be affixed to the reinforcing strip 144 at various selected points by means of a plurality of loops 158, made of suitable stitching, or by other suitable means.

5 The just described cable arrangement when used provides a solid member upon which the assembled canoe may slide without damaging the canvas cover.

10 The preceding description discloses a preferred embodiment of my invention, and it should be understood that numerous changes may be made therein without departing from the appended claims. In the claims the words "boat" and "canoe" are meant to include other similar types 15 of watergoing craft.

I claim:

1. In combination with a boat, canoe or the like comprising a plurality of separably connected hull sections, a flexible, waterproof cover 20 upon the outside of said sections for rendering said sections watertight, a strong resilient cord running along the upper edge of said cover and fixedly attached thereto at a plurality of points intermediate the ends of the cord, and holding 25 means attached at a plurality of points to said sections intermediate the ends of the assembled structure for engaging said cord.

2. In combination with a boat, canoe or the like comprising a plurality of separably connected hull sections having gunwales, a flexible, waterproof cover upon the outside of said sections for rendering said sections watertight, a strong resilient cord running along the upper edge of said cover and fixedly attached thereto 35 at a plurality of points intermediate the ends of the cord, and holding means attached to each of said sections on the outside thereof near the gunwales and above the point of attachment of said cord means to said cover for engaging said 40 cord means.

FELIX A. AIMONETTI.
